OILSTOVE

George Brantley, Tampa, Fla., assignor of one-third to Hattie Smith, Tampa, Fla.

Application July 22, 1939, Serial No. 285,988

3 Claims. (Cl. 67—10.1)

This invention relates to improvements in oil-stoves, the general object of the invention being to provide means for facilitating lighting of the stove and also to provide means whereby the movable parts can be readily adjusted.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a front view of a portion of an oil-stove showing the invention applied thereto.

Figure 2 is a vertical sectional view through Figure 1 showing the parts in position with a wick to be lighted.

Figure 3 is a top plan view of the combustion chamber removed.

Figure 4 is a section on the line 4—4 of Figure 3 with some of the parts shown in elevation.

Figure 5 is a fragmentary view with parts in section, showing the wick member in raised position with the snuffer over the wick of the lighter so as to extinguish the flame of the lighter.

Figure 6 is a view similar to Figure 5 but showing the wick carrying member in fully raised position.

Figure 7 is a view of the lighter wick with the tube which carries the wick.

Figure 8 is a section on the line 8—8 of Figure 2.

Figure 9 is a fragmentary plan view of the wick carrying member and showing the snuffer.

Figure 10 is a fragmentary view showing how the standard of the combustion chamber slides through an opening in a supporting part of the standard.

Figure 11 is a bottom plan view of the combustion chamber.

In these drawings the letter A indicates a portion of the structure of a stove which includes the dial a and the numeral 1 indicates a shaft journaled in the supporting structure and having one end passing through the dial with the handle 2 attached to said end, this handle carrying the pointer 3 for cooperating with the indicia on the dial in the usual manner. The combustion chamber is shown at C and a shaft 4 depends from the chamber and has a reduced part 4' which passes through a hole 5 in a part

of the supporting structure. This member 4 passes through the wick holder or reservoir 6, the wick of which is shown at 7 and a link 8 is pivoted to a part of the member 6 and to a link 9 by a pin 10 and said link 9 has a slot 11 therein through which a pin 12 passes which is carried by a part of the supporting structure. This link 9 is connected to a crank 13 actuated by rocking movement of the handle 2 and as will be understood when the handle 2 is moved in a clockwise direction the member 6 will be raised against the combustion chamber C and further movement will cause the member 6 to raise the combustion chamber and during this movement the shaft 4 is raised as shown in Figure 10. When the member 6 is lowered the combustion chamber will move downwardly with it until the shoulder 4", formed at the junction of the main part of the shaft 4 with the reduced part 4' comes to rest on the supporting structure when further movement of the combustion chamber will cease but the member 6 will continue to move downwardly so that it will be spaced from the combustion chamber and this permits the wick to be lighted. The lighting means includes tubular part 15 fastened to but out of communication with a part of the supply pipe 16 of the stove with the upper end of the tubular member 15 internally threaded to receive the threaded enlargement 17 of a wick tube 18, the wick being shown at 19. Of course, the tube 18 holds a portion of the wick 19 in the member 15 which is to receive a very volatile liquid such as that used in cigar lighters. Attached to this tubular member 15 such as by solder 20 is a tubular member 21 having its lower end closed by a plug 22 which is threaded in said lower end and which acts to adjust the tension of a spring 23 in the tubular member 21 for holding a flint 24 adjacent a knurled wheel 25 fastened to a shaft 26 which has a part journaled in the upwardly extending reduced parts 27 of the tube 21. This shaft extends through a supporting bracket 27' forming part of the dial a and has a handle 28 at its front end whereby the wheel can be turned to cause the teeth thereon to strike the flint thus producing sparks which will ignite the projecting end of the wick 19. The flange 29 of the member 6 is cut out to provide an opening 30 through which the wick 19 will partly extend when the member 6 is in its lowered position so that when protruding end of the wick 19 is ignited it will ignite the wick 7 in the member 6. Then after the wick 7 has been ignited the handle 2 is turned to raise the member 6 and as the mem-

- ber 6 moves upwardly a substantially U-shaped member 31 attached to a side part of the member 6 moves over the protruding end of the wick 19 so as to snuff or extinguish the flame and 5
5 then the member 6 will engage the bottom of the combustion chamber C and the products of combustion from the burning wick 7 will enter the combustion chamber so as to heat the same, the combustion chamber being raised by continued movement of the member 6 until finally the snuffer 31 passes above the wick 19 as shown in Figure 6. A depending part 33 is fastened to the bottom of the combustion chamber C for closing the opening or recess 30 in the flange 29 10
10 of the member 6 so as to prevent the entrance of air to this recess which might interfere with the proper function of the stove.
15

Thus it will be seen that I have provided simple means for lighting the wick of an oilstove 20 by simply turning a toothed wheel for producing sparks from a flint for igniting the wick of a lighting device which, in turn, lights the wick of the stove and then as the wick carrying member of the stove is raised the wick of the lighting device is automatically extinguished.
25

It is thought from the foregoing description that the advantages and novel features of the invention will be readily apparent.

It is to be understood that changes may be 30 made in the construction and in the combination and arrangement of the several parts provided that such changes fall within the scope of the appended claims.

Having described the invention, what is claimed 35 as new is:

1. An igniting attachment for an oilstove which includes a wick carrying member and means for raising and lowering the same, said attachment comprising a reservoir containing a volatile liquid and a wick, spark producing means for lighting the last-mentioned wick, said last-mentioned wick being located adjacent the first-mentioned wick when the carrying member is in lowered 40

position whereby the second wick will ignite the first wick and means for automatically extinguishing the second wick when the wick carrying member is raised.
5

2. An igniting attachment for an oilstove which includes a wick carrying member and means for raising and lowering the same, said attachment comprising a reservoir containing a volatile liquid and a wick, spark producing means for lighting the last-mentioned wick, said last-mentioned wick being located adjacent the first-mentioned wick when the carrying member is in lowered position whereby the second wick will ignite the first wick and means for automatically extinguishing the second wick when the wick carrying member is raised, said extinguishing means including a yoke-shaped member on the wick carrying member through which the wick carrying part of the attachment passes and which passes over the second wick upon raising movement of the wick carrying member of the stove.
10
15
20

3. An igniting attachment for an oilstove which includes a combustion chamber, a wick carrying reservoir and means for raising and lowering the wick carrying reservoir, said attachment comprising a tubular member containing a volatile liquid and a small wick, lighting means including a knurled wheel for lighting the small wick, said small wick being located adjacent the wick of the reservoir when the reservoir is in lowered 30 position and said reservoir having a recess therein for permitting the flame from the small wick to reach the flame of the wick in the reservoir, a substantially U-shaped member connected with a side portion of the reservoir and surrounding the part which carries the small wick for extinguishing the flame of the small wick when the reservoir is raised and a projecting part at the bottom of the combustion chamber for closing the recess when the reservoir is raised 40 against the lower part of the combustion chamber.
